James Clarke

Silvers Galant

The Schedule of proofs to witness Letters Patent and making part of the same containing a description in the words of the said James Clarke himself of his improvement in the machine called a "self-regulating conduit" for passing water around land bank from a high or to a lower level.

The bottom of the conduit connecting with the upper level of the canal must coincide with the bottom of that level, and be carried to such a point between the upper and lower levels of the canal as shall be found most convenient for the construction of the regulating gate. The lower level of the conduit must be on a plain with the lower level of the canal, or may be sunk as much lower as the particular circumstances of the case may require. The dimensions of the conduit must be regulated in proportion to the quantity of water which it is intended to pass. At the connection of the two levels of the conduit, the regulating gate must be placed & constructed in the following manner. Two or more mud sills are framed together and are placed horizontally at the bottom of the lower level of the conduit, into which two upright gate posts are placed one on each side of the conduit and extending from the bottom of the lower to the top of the upper level, these posts to be supported by a cap-sill, braces and longitudinal frame work, covered with plank extending each side of the gate, so as to conduct the water to the gate, and to serve as an apron to convey the water over the air box buoy or float, a groove or rabbet must be cut in each of the gate posts so as to receive the gate, and extending from the top of the posts downwards a sufficient distance to admit the top of the gate to be drawn down to the bottom of the upper level of the conduit. When the side of the gate shall be such as to prevent it sliding, easily in the ground, or safety metal boxes or friction blocks will

in Part 3d

be placed so as to admit a free action of the gate. The gate must be constructed of planks well jointed and bound together and be of a height corresponding with the depth of the water intended to be maintained on the upper level. This gate is connected with an air box, buoy or float placed in the lower level, which box, buoy, or float, must be of a size and buoyancy sufficient to raise the gate as the water shall rise in the lower level. This box, buoy, or float is connected with the gate in the following manner.

Two or more screws are required, with flat heads resting on the top of the box, buoy, or float, and secured to it by metal plates having holes in them sufficiently large to admit the shank of the screws to pass upwards through them. When these plates are fastened to the box, buoy, or float, the heads of the screws will turn under them, in the manner of a screw. holes corresponding with the screws, must be bored in the lower edge of the gate, and be of sufficient depth to admit the box, buoy, or float, and the gate to be turned together or apart so as to maintain any required quantity of water on either level.

Screw nuts must be placed in these holes so as to govern the gate. Thickened shanks in these shanks, near the box, buoy, or float to admit the end of a turning bar or lever for the greater convenience of working them. When it is intended to maintain a greater quantity of water on the upper than the lower level, the gate must be secured from the box, buoy, or float, when the greater quantity is required on the lower level, the gate must be secured towards the box, &c. The operation of the machine will be as follows. The water impinging the conduit will flow over the top of the gate into the lower level, as the water rises in the lower level, the buoyancy of the box, buoy, or float, will force the gate upwards until the required quantity is obtained, in the lower level, when the upper section of the conduit will be closed by the gate. Should the water sink in the lower

link in the lower canal. The weight of the box being sufficient
will draw the gate downwards so as to admit the water 10 feet
over its upper edge thus producing a regular supply and such
depths of water in the canal at all times as may be desired.
